UNITED STATES PATENT OFFICE.

CHARLES R. KEERAN, OF CHICAGO, ILLINOIS.

KNIFE.

1,234,345.

Specification of Letters Patent. Patented July 24, 1917.

Application filed April 15, 1916. Serial No. 91,385.

To all whom it may concern:

Be it known that I, CHARLES R. KEERAN, a citizen of the United States, residing at Chicago, county of Cook, and State of Illinois, have invented certain new and useful 5 Improvements in Knives, of which the following is a specification.

This invention relates to knives of the type wherein the blades are pivoted to the 10 haft, and is concerned particularly with means for opening up the blades.

Knives such as those ordinarily carried in the pocket are usually provided with a spring which bears against the tang of each 15 blade to hold the blade in open or closed position. Such a knife is opened by inserting the thumb nail into a groove formed in the edge of the blade, and then grasping the blade with the fingers to complete the 20 opening movement. Great difficulty is often encountered in opening a blade in this manner, due to the fact that the thumb nail alone must start the blade against the tension of the spring. It is a primary object 25 of my invention to provide a knife, wherein there are means for starting the blade without the use of the thumb nail. Other objects of my invention include the provision 30 of opening means for each blade located within the haft, which are simple and reliable in operation and inexpensive of construction; means which operate without undue friction; means which sustain each blade after being started, in partially open 35 position, against the tension of the spring; and means which are automatically reset when the blade is closed. These and other objects of my invention will more clearly hereinafter appear from the specification 40 and claims and from the accompanying drawings in which:—

Figure 1 is a side elevation of a simple form of pocket knife, the blades of which are provided with self-opening means of the 45 present invention;

Fig. 2 is a longitudinal section, enlarged, of the blade-opening means, one end only of a single blade being exhibited;

Fig. 3 is a view similar to Fig. 2, showing 50 the blade in started or partially open position;

Fig. 4 is a view similar to Fig. 2, showing the blade at a point of rest before being fully opened;

55 Fig. 5 is a view similar to Fig. 2, showing the blade fully opened;

Fig. 6 is a view similar to Fig. 2, showing the blade partially closed and the wedge member reset to its normal position; and

Figs. 7 and 8 are transverse sections 60 through the knife taken on lines 7—7 and 8—8, respectively, of Fig. 2.

I have illustrated in the drawings a simple form of knife comprising a haft 9, the walls 10 of which are secured in place by 65 pins or studs 11 in the ordinary manner. One or more blades 12 are pivotally secured to the haft, a spring 13 being also provided to hold each blade in closed or open position. The present invention may be employed with various kinds of knives, such, 70 for example, as those in which scales are secured to linings formed upon the haft. It may also be applied to knives equipped with one or more blades at either end of the haft. 75 For these reasons the description to follow will deal with but one blade; for a plurality of blades the operative parts of my invention will merely be duplicated. The terms "inward" and "outward," as used 80 hereinafter, will be understood to designate directions relatively toward and from the center of the knife.

The blade of the present invention is formed with a tang 14 reduced at its extremity 15, and provided with a hole through which a pin 16 is passed to pivotally mount the blade within the haft. The end face 17 of the tang extremity may be flattened, if desired, to provide a resting 85 surface for the blade when it is opened up substantially half way, as shown in Fig. 4. When the blade is closed there will be a bearing upon a hump 18 which projects from the face 19 of the tang at its extremity, 90 the hump being situated outwardly of the pivotal center of the blade to normally hold it closed.

The spring 13 near its extremity is provided as shown in the several figures of 100 the drawing, with a transverse slot 20 having end walls 21 and 22. Within the slot 20 is located a roller 23 of less diameter than the width of the slot, and arranged to roll thereacross. The roller bears against the 105 spring 13 on one side, and against a wedge member 24 on the other side. This wedge member consists of a head 25 arranged to move within a second slot 26 formed at the extremity of the spring, the inner end 27 110 of the head being arranged to not pass beyond the extremity of the spring; a neck 28

formed with inclined shoulders 29 and 30 on its upper face, and with a shoulder 31 on its lower face, which limits the outward movement of the wedge member when in engagement with the roller 23; and an acting end 32 beveled at a suitable angle to provide a cam surface which engages with and rides upon a sleeve roller 33 loosely mounted upon a pin 34. When the wedge member is moved toward the sleeve roller, the cam surface rides thereupon in such a manner that the wedge member is forced to an upward position, similar to that shown in Fig. 3.

15 When the blade is closed the hump 18 normally rests upon the inclined shoulder 29, as appears in Fig. 2, the hump and shoulder affording the principal point of engagement between the wedge member and the blade. The pressure of the spring is exerted through the roller 23 against the wedge member which in turn engages with the blade at the point of the hump 18 located outwardly of the pivotal center of the 25 blade, thus causing the blade to be normally held tightly in closed position.

The operation of starting the blade will be clearly understood by reference to the several figures of the drawing. To open 30 the blade, pressure first is applied to the head 25 which normally protrudes slightly beyond the end of the haft, to impart an inward driving movement to the wedge member. As the inner end 27 of the head 35 is arranged to always lie slightly forward of the extremity of the spring, as shown in Fig. 2, no extraneous particles can easily enter into the slot 26 to obstruct the inward movement of the wedge member. For the 40 same reason, the head of the wedge member is prevented from catching or tearing the clothes whenever the knife is carried in the pocket. When sufficient pressure is applied, the wedge member will be moved inwardly, 45 riding upon the roller 23 to the limit of its movement within the slot 20; the further movement of the wedge member is accomplished by its sliding over the roller. The roller is important chiefly in that it aids in 50 starting more easily the movement of the wedge member. I find it unnecessary on this account to extend the slot 20 further than merely to provide for the limited rolling action of the roller as described. The 55 inward movement of the wedge member will also cause the cam surface 32 to ride upon the sleeve roller 33, so that the wedge member will engage with the tang of the blade at a point situated a considerable distance 60 from its pivotal mounting. This wedge action is entirely sufficient to overcome the pressure of the spring communicated through the narrow neck portion of the wedge member to the hump 18, at a point 65 relatively close to the pivotal center of the

blade. The blade accordingly will be opened to the distance that the wedge member forces it. The tendency for the blade to close under the pressure exerted by the spring against the hump at the extremity 70 of the tang when the blade is in the position of Fig. 3 is resisted by the friction between the wedge member and the tang which tends to prevent the wedge member from sliding back off of the sleeve roller 33 to normal 75 position, so that the blade is prevented from closing when once started in the manner described. Having started the blade, the fingers can readily seize the blade to open it 80 fully.

The position of the wedge member will remain unchanged during the further opening movement of the blade. As appears from Fig. 4, the hump 18 is required to ride up upon the inclined shoulder of the wedge 85 member, thereby depressing the spring in order that the blade may be swung through an arc of 90° or more. In completely open position, the parts will be related in the manner shown in Fig. 5. It will be observed 90 in this position that the pressure exerted by the spring is communicated to the extremity of the blade tang in such a way as to insure the maintenance of the blade in open position. 95

In the present knife it is important that the wedge member should be automatically reset when the blade is closed. This is accomplished in the following manner: When the blade is moved from the position of Fig. 100 5 to that of Fig. 6, the portion of the tang extremity in engagement with the wedge member will be moved outwardly, thus tending by friction to move the wedge member in the same direction until it has reached the 105 normal position shown in Figs. 2 and 6. In any other than normal position the wedge member will be resting upon both the roller 23 and the sleeve roller 33, in consequence of which the return movement of the wedge 110 member is greatly facilitated. For these reasons the closing of the blade will automatically cause a simultaneous retraction of the wedge member to normal position. This retraction, moreover, will be completed in a 115 very short space of time, being aided by the pressure of the spring and the two rollers upon which the wedge member rides. It is thus apparent that when the blade is completely closed to the position shown in Fig. 120 2, the wedge member will have been reset to its normal position where it is available for again starting the blade in the manner previously described.

If the blade is started to the position 125 shown in Fig. 3, and is not further opened, the wedge member may be reset by forcibly closing the blade. Under such circumstances the beveled acting end of the wedge member will cause the wedge member to be rear- 130

wardly moved, and be reset in the position shown in Fig. 2. This is obviously a desirable end, as otherwise the resetting of the wedge member could be accomplished only 5 by opening the blade to a substantially half way position and then closing the same.

From the foregoing description, as well as from the several figures of the drawing, it will be seen that the blade opening means 10 are located within the haft where they are secure against damage or displacement. The parts utilized for opening the blade occupy but little space. They are both simple and reliable in operation, and may be manu- 15 factured at small expense.

I claim:

1. A knife embodying, in combination, a haft, a blade provided with a tang, a pivotal mounting for the blade tang within the 20 haft, a spring within the haft, a wedge member between the spring and tang and longitudinally movable within the haft, and means for forcing the wedge member against the blade to partially open the same when 25 the wedge member is moved longitudinally within the haft, substantially as described.

2. A knife embodying, in combination, a haft, a blade provided with a tang, a pivotal mounting for the blade tang within the 30 haft, a spring within the haft, a wedge member between the spring and tang longitudinally movable within the haft, and means co-operating with the wedge member for partially opening the blade when the wedge 35 member is moved longitudinally within the haft, there being a hump upon the tang in engagement with the wedge member for normally holding the blade closed, substantially as described.

40 3. A knife embodying, in combination, a haft, a blade provided with a tang, a pivotal mounting for the blade tang within the haft, a spring within the haft, a wedge member between the spring and tang longitudinally 45 movable within the haft, anti-friction members between the wedge member and the spring, one of said anti-friction members co-operating with the wedge member to partially open the blade when the wedge mem- 50 ber is moved longitudinally within the haft, substantially as described.

4. A knife embodying, in combination, a haft, a blade provided with a tang, a pivotal mounting for the blade tang within the 55 haft, a spring within the haft, a wedge member between the spring and tang longitudinally movable within the haft, the inner end of the wedge member being beveled, an anti-friction member in engagement with the 60 beveled end of the wedge member and ar- ranged to co-operate therewith when the wedge member is moved longitudinally within the haft to partially open the blade, substantially as described.

65 5. A knife embodying, in combination, a

haft, a blade provided with a tang, a pivotal mounting for the blade tang within the haft, a spring within the haft, the spring having a slot arranged transversely thereof, a roller within the slot arranged to travel there- 70 within, a wedge member between the spring and tang longitudinally movable within the haft and arranged to ride upon the roller, and means co-operating with the wedge member for partially opening the blade 75 when the wedge member is moved longitudinally within the haft, substantially as described.

6. A knife embodying, in combination, a haft, a blade provided with a tang, a piv- 80 otal mounting for the blade tang within the haft, a spring within the haft, the spring having a slot arranged transversely thereof, a roller within the slot arranged to travel thereacross, a wedge member between the 85 spring and tang longitudinally movable within the haft, and arranged to ride upon the roller, a shoulder upon the wedge member arranged to engage with the roller to limit the outward movement of the wedge 90 member, and means co-operating with the wedge member for partially opening the blade when the wedge member is moved lon- 95 gitudinally within the haft, substantially as described.

7. A knife embodying, in combination, a haft, a blade provided with a tang, a pivotal mounting for the blade tang within the haft, a spring within the haft, the end of the spring being cut away to provide a wall 100 within the haft, a wedge member between the spring and tang longitudinally movable within the haft, a head upon the wedge member arranged to engage with the spring wall within the haft to limit the inward 105 movement of the wedge member, and means co-operating with the wedge member for partially opening the blade when the wedge member is moved longitudinally within the haft, substantially as described. 110

8. A knife embodying, in combination, a haft, a blade provided with a tang, a pivotal mounting for the blade tang within the haft, a spring within the haft, a wedge member between the spring and tang longitudinally 115 movable within the haft, an anti-friction member between the wedge member and the spring, said anti-friction member co-operat- 120 ing with the wedge member to limit the movement of the latter in one direction, and other means co-operating with the wedge member for partially opening the blade when the wedge member is moved longitudinally within the haft, substantially as described. 125

9. A knife embodying, in combination, a haft, a blade provided with a tang, a pivotal mounting for the blade tang within the haft, a spring within the haft, a wedge member between the spring and tang longitudinally 130

movable within the haft, means coöperating with the wedge member for partially opening the blade when the wedge member is moved longitudinally within the haft, and 5 other means coöperating with the wedge member for preventing retraction thereof when the blade is opened, substantially as described.

10. A knife embodying, in combination, a haft, a blade provided with a tang, a pivotal mounting for the blade tang within the haft, a spring within the haft, the spring being provided with the slot extending thereacross, a roller arranged to travel across 15 the slot, a wedge member between the spring and tang longitudinally movable upon the roller within the slot, the inner end of the wedge member being beveled, a sleeve roller in proximity to the beveled end of the wedge 20 member arranged to raise the inner end thereof when the wedge member is moved within the haft, whereby the blade is partially opened, a hump upon the outer end of the tang, a shoulder upon the wedge member 25 engaged by the hump, the hump and shoulder coöperating to prevent return movement of the wedge member when the blade is partially opened, substantially as described.
30. 11. A knife embodying, in combination, a haft, a blade provided with a tang, a pivotal mounting for the blade tang within the haft, a spring within the haft, a wedge member between the spring and tang longitudinally 35 movable within the haft, a head upon the wedge member normally projecting beyond the end of the haft, a neck adjacent the head formed with an inclined shoulder, a hump on the tang extremity arranged to 40 ride upon the shoulder when the wedge member is moved within the haft, and means coöperating with the wedge member for partially opening the blade when the wedge member is moved within the haft, substantially 45 as described.
12. A knife embodying, in combination, a haft, a blade provided with a tang, a pivotal mounting for the blade tang within the haft, a spring within the haft, the extremity of 50 the spring being cut away to provide a clearance therein, a wedge member between the

spring and tang longitudinally movable within the haft, a head upon the wedge member normally projecting beyond the haft, and arranged to move within the clearance of the spring extremity when the wedge member is advanced into the haft, and means for limiting the outward movement of the wedge member, substantially as described. 55

13. A knife embodying, in combination, a haft, a blade provided with a tang, a pivotal mounting for the blade tang within the haft, a spring within the haft, the extremity of the spring being cut away to provide a 60 clearance therein, a wedge member between the spring and tang longitudinally movable within the haft, the wedge member being provided with a head portion which normally projects beyond the haft, and arranged to move within the clearance of the 65 spring extremity when the wedge member is advanced into the haft, and means for limiting the movement of the wedge member outwardly of the haft to permit the 70 head to emerge but partially from the haft, substantially as described. 75

14. A knife embodying, in combination, a haft, a blade provided with a tang, a pivotal mounting for the blade tang within the 80 haft, a spring within the haft, a wedge member between the spring and tang and longitudinally movable within the haft, the wedge member being arranged to forcibly engage with the tang to partially open the 85 blade when the wedge member is moved longitudinally within the haft, substantially as described.

15. A knife embodying, in combination, a haft, a blade provided with a tang, a pivoted 90 mounting for the blade tang within the haft, a spring within the haft, and a member longitudinally movable between the spring and tang and arranged to forcibly engage with the tang, to partially open the blade 95 when the member is moved longitudinally of the knife, substantially as described.
